UNITED STATES PATENT OFFICE.

DAVID L. WINTERS, OF EDGEWATER, MARYLAND.

METHOD OF AND MEANS FOR SUPPLYING INTERNAL-COMBUSTION ENGINES WITH FUEL.

1,337,338.

Specification of Letters Patent. Patented Apr. 20, 1920.

Application filed January 4, 1917. Serial No. 140,655.

To all whom it may concern:

Be it known that I, DAVID L. WINTERS, a citizen of the United States, residing at Edgewater, in the county of Anne Arundel and State of Maryland, have invented certain new and useful Improvements in Methods of and Means for Supplying Internal-Combustion Engines with Fuel, of which the following is a specification.

This invention relates to the method of and means for supplying internal combustion engines with fuel, and particularly to the method of supplying such engines with less volatile and more economical fuel, composed of a mixture of gasolene and kerosene.

The primary object of the invention is the provision of a method and means whereby, and without manual re-adjustment of the valves controlling the mixture, the engine is supplied at certain times with gasolene only, and at other times with a mixture of gasolene and kerosene.

A further object of the invention is the provision of a method and means whereby, and without manual re-adjustment of the valves controlling the mixture, the consumption of kerosene is increased or diminished in accordance with the needs of the engine, without increasing or diminishing the consumption of gasolene.

A further object of the invention is the provision of a method and means whereby the fuel after entering the fuel reservoir in the carburetor, is subjected to heat other than the heat generated within the engine, to render it more suitable for combustion.

A still further object of the invention is the provision of a method and means whereby the amount of heat to which the fuel is thus subjected is increased or diminished in proportion to the amount of fuel being consumed.

Referring to the drawings, Figure 1 is a side elevation of a portion of a motor-car, partly broken away, and represents my invention as applied to the engine thereof; Fig. 2 is a detail perspective of a portion of the gasolene pipe, and the valves therein; Fig. 3 is a sectional view of a carburetor, showing the fuel reservoir thereof, an electric heater attached thereto, and a rheostat for such heater; Fig. 4 is a detail perspective of the levers to effect co-operative regulation of the fuel passing to the engine, and the heat to which the fuel is being subjected.

Like reference numerals denote like parts wherever used.

The carburetor control shown herein, is the subject matter of my application filed December 27, 1916, Serial Number 139,227. 60

5 is an internal combustion engine, 6 represents the kerosene supply; 7 is a supply of gasolene positioned at a greater elevation than the kerosene, or under greater air pressure than the kerosene, which ever is most 65 convenient, for a purpose hereafter described. 8 is a carburetor, and 9 is the operating lever to control the passage of air and fuel therethrough; 10 is a feed pipe to supply the carburetor with kerosene, 11 is a 70 feed pipe to supply the carburetor with gasolene; and 12 is a check valve in the feed pipe 10, the purpose of which is to prevent the gasolene from backing up into the kerosene container 6. 13 and 14 are the usual 75 service valves, to be closed when repairs are being effected. 15 is an emergency valve in the gasolene feed pipe, for a purpose hereafter described. 16 is a by-pass in the gasolene feed pipe, surrounding the emergency valve 15. 17 is a needle valve in the by-pass 16, for a purpose hereafter described. 18 is a pipe to supply the carburetor with heated air, from the exhaust manifold of the engine, in the usual manner. 80 Feed pipes 10 and 11 are joined together at the fuel entrance to the carburetor. The normal position of valve 15 is closed, and the normal position of the needle valve 17 is that which will supply the engine with 85 sufficient gasolene for starting and for running idle, or under very light load conditions.

The object in positioning the gasolene supply 7 at a greater elevation than the 95 kerosene supply 6, is to insure, by the greater pressure in the gasolene feed pipe, the consumption of gasolene at all times to the extent provided by this adjustment of the needle valve 17. 100

Assuming that the valves are in their normal positions, as thus far described, the operation is as follows:

The engine is started in the usual manner and is being operated on gasolene only, because the adjustment of the needle valve 17 is such that it will provide fuel slightly in excess of the quantity required by the engine while running idle. The engine and the exhaust manifold become quickly heated 110

in this manner, and, because of the heat in the engine, and also because heated air is now being supplied to the carbureter through the air inlet 18, conditions have 5 been established under which a less volatile fuel may be successfully utilized.

When the engine is operated under varying conditions of load, this adjustment of the needle valve 17 prevents the engine 10 from receiving a sufficient amount of fuel from the gasoline supply. Under these conditions the pressure in the feed pipes 10 and 11 becomes equalized, and the carbureter is supplied with both gasoline and 15 kerosene.

When the engine is consuming more than twice the amount of fuel being supplied by this fixed adjustment of the needle valve 17, the consumption of kerosene is greater than 20 the consumption of gasoline, and when the engine is consuming less than twice the amount of fuel being supplied by this fixed adjustment of the needle valve 17, the consumption of kerosene is less than the consumption of gasoline.

This is highly desirable because, when the engine is being operated under greatly throttled condition, the consumption of the fuel is not accompanied by sufficient heat 30 and compression to insure the efficient combustion of a less volatile mixture.

I realize that the maximum efficiency of neither the engine or the carbureter can be obtained by the use of fuel less volatile than 35 gasoline, and I therefore provide the operator with the emergency valve 15, by means of which he can instantly provide the carbureter with an unlimited supply of gasoline, without disturbing the adjustment of 40 the needle valve 17.

In order to render the fuel as volatile as possible, I provide the fuel reservoir 19 of the carbureter 8 with an electric heater 20, provided with the usual heating coils 21, the 45 usual conduits 22, leading from a battery or dynamo circuit, a conduit extension 23, leading to a rheostat 24, provided with an operating lever 25. The bottom of the fuel reservoir 19 is preferably composed of very 50 thin metal, and the float 26 therein, is preferably of a size that will almost fill the reservoir 19.

The object of this construction is to permit of the quick heating of the fuel in the 55 reservoir 19, upon the operation of the rheostat lever 25. As will be seen a comparatively thin body of fuel will be present between the bottom of the float 26 and the bottom of the reservoir 19 to be subjected to the 60 heat of the coils 21, this resulting in the quick heating of the fuel.

Because of a partial vaporization of the fuel in the reservoir 19 under this condition of operation, I provide in the upper portion 65 of this reservoir, a vent 27 through which

this vapor may pass into the mixing chamber 28.

This is important, because an accumulation of vapor in the upper part of the reservoir 19 would tend to lower the normal level 70 of the liquid fuel therein, and seriously affect the efficient operation of the liquid fuel valve 29.

30 is a pipe to supply the fuel containers 6 and 7 with air pressure in the usual manner, and 31 are gages to indicate the fuel levels therein.

The kerosene container 6 may be supplied with any fuel less volatile than gasoline. For instance, a mixture of gasoline and 80 kerosene may be found desirable under some conditions of operation, especially in cold weather, when even gasoline is not sufficiently volatile to permit of efficient combustion, without first being heated. It is preferable that the heating coils 21 be supplied with current from both a battery and dynamo, because by this method of operation, the fuel in the reservoir may be heated by means of the battery circuit before the engine is 85 started, and thereafter, by means of the dynamo circuit. Such operation would permit of the use of a fixed or predetermined mixture of gasoline and kerosene, since by 90 this method of heating the fuel in the reservoir 19, it can be rendered sufficiently volatile for the needs of the engine, under all 95 conditions of operation.

It will be understood that the rheostat lever 25 may be employed as shown in Figs. 100 3 and 4, or may be dispensed with as shown in Fig. 1, wherein the lever 9 operates both the valves in the carbureter, and the rheostat of the heater. Also, any well known means may be employed to maintain a uniform difference in pressure of the gasoline and kerosene supplies. In the normal operation of the car this difference in pressure remains substantially the same, because of the consumption of gasoline and kerosene in 105 approximately the same amounts.

I realize that considerable variation is possible in the details of construction and arrangement of parts without departing from the spirit of my invention, and I therefore do not limit myself to the specific form shown and described.

Having thus described my invention what I claim as new and desire to secure by Letters Patent is:

1. In combination with the carbureter of an internal combustion engine, of means for supplying said carbureter with a fixed supply of volatile fuel under all conditions of operation, and with an additional supply of 115 less volatile fuel only when the engine is operating under loaded condition.

2. In combination with the carbureter of an internal combustion engine, of means for supplying said carbureter with a fixed rela- 120

tively limited supply of volatile fuel under all conditions of operation, and with a relatively unlimited additional supply of less volatile fuel only when the engine is operating under loaded conditions.

3. In combination with the carbureter of an internal combustion engine, of means for supplying such carbureter with a restricted supply of volatile fuel under all conditions 10 of operation, and with an additional supply of less volatile fuel, the supply of said last-referred to fuel being automatically controlled by the load on the engine.

4. In apparatus of the character described, 15 the combination of a carbureter, a supply of volatile liquid under pressure, a supply of less volatile liquid under less pressure than the other liquid, and automatically operating means to supply the carbureter with 20 either or both of said liquids during the use thereof.

5. In apparatus of the character described, the combination of a carbureter, a supply 25 of volatile liquid under pressure, a supply of less volatile liquid under less pressure than the other liquid, and normally open conduits to supply the carbureter with both of said liquids one of the conduits being provided with a restricted portion whereby 30 the ratio of supply between the volatile and less volatile liquids is automatically varied according to the load on the engine.

6. In apparatus of the character de-

scribed, the combination of a carbureter, a supply of volatile liquid under pressure, a 35 supply of less volatile liquid under less pressure than the other liquid, normally open conduits to supply the carbureter with both of said liquids, and valve means to restrict the consumption of the first named liquid 40 and to automatically increase the supply of less volatile liquid as the load on the engine increases.

7. In an apparatus of the character described, in combination, a carbureter, a supply 45 of volatile fuel, a supply of less volatile fuel under less pressure than said first mentioned supply, conduits leading from said supplies terminating in a single pipe adjacent the carbureter, a check valve positioned to prevent the first-named fuel from backing up through the conduit of the last-named fuel, the conduit connected with the first supply having a relatively limited flow, and the conduit connected with the second 50 supply having a relatively unlimited flow whereby as the load increases on the engine the proportion of less volatile fuel fed to the carbureter will be automatically increased.

In testimony whereof I affix my signature 55 in presence of two witnesses.
